(57) **CLAIM**

We claim the ornamental design for a tripod for an electronic device, as shown and described.

DESCRIPTION

FIG. 1 is a front elevational view of a first embodiment of a tripod for an electronic device;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof;

FIG. 7 is a top plan view of the tripod for an electronic device in a deployed state;

FIG. 8 is a bottom plan view thereof;

FIG. 9 is a rear elevational view thereof;

FIG. 10 is a front elevational view thereof;

FIG. 11 is a right side elevational view thereof;

FIG. 12 is a left side elevational view thereof; and,

FIG. 13 is a perspective view thereof.

The broken lines are for illustrating unclaimed portions of the tripod for an electronic device; the broken lines form no part of the claimed design.

1 Claim, 12 Drawing Sheets
